(57) **CLAIM**

The ornamental design for a tail lens assembly, as shown and described.

DESCRIPTION

FIG. 1 is a right side perspective view of the tail lens assembly of the present design;

FIG. 2 is a right side perspective view of the tail lens assembly of FIG. 1, showing the cover of the tail lens assembly removed;

FIG. 3 is a front elevational view of the tail lens assembly of FIG. 1;

FIG. 4 is a right side elevational view of the tail lens assembly of FIG. 1;

FIG. 5 is a top plan view of the tail lens assembly of FIG. 1; and,

FIG. 6 is a right side perspective view of the tail lens assembly of FIG. 1, showing the tail lens assembly installed on a vehicle.

Phantom lining, where used, is for illustrative purposes only and is not intended to limit the claimed design to the features shown in phantom.
